UNITED STATES PATENT OFFICE.

JOHN THOMAS HASKELL, OF NORWALK, OHIO, ASSIGNOR OF ONE-HALF TO
H. E. STREATORE, OF SAME PLACE.

SCAFFOLDING.

SPECIFICATION forming part of Letters Patent No. 295,389, dated March 18, 1884.

Application filed November 27, 1883. (No model.)

To all whom it may concern:

Be it known that I, JOHN T. HASKELL, a citizen of the United States, residing at Norwalk, in the county of Huron and State of Ohio, have invented a new and useful Scaffold, 5 of which the following is a specification, reference being had to the accompanying drawings.

My invention relates to scaffolding, the object being to provide a scaffold which may be readily adjusted to any height, and, further, to provide improved means for retaining the scaffold in an elevated position when in use.

The invention consists, broadly, in the combination, with supporting-beams, of a frame or scaffold adapted to slide thereon, and means for locking said scaffold at any desired point on the supporting-beams.

In the drawings, Figure 1 is a perspective view of my device. Fig. 2 is a side elevation of the same, and Fig. 3 is a longitudinal vertical section.

A A' represent vertical beams, which are secured together at their upper ends by means 25 of a bolt, a', which allows of a limited lateral movement of said beams, and upon which is mounted a pulley, a'', between said beams A A'.

B represents my improved scaffold, which 30 is constructed in the following manner:

C C' represent the side beams, to the lower ends of which are secured transverse braces b b'. To the upper ends of these beams C C' are secured beams or braces c c'. The top 35 edge of the brace c is on the same plane with the top of the beams C C', while the bar c' is secured a short distance below the upper edge of the beams C C', and serves as a support for the beam D, the end of which is mortised in 40 the brace c'. The other end of this beam D is slotted to receive an idler or roller, d', which bears against the wall of the house or other object in connection with which the scaffold is used when said scaffold is to be raised or lowered.

E E' represent bracing-beams secured, respectively, to the sides of the beam D and to the beams C C' near their lower ends.

F represents a brace secured, one end to the 50 bar c and the other or lower end to the bar b.

This brace or upright F is slotted near its upper end to receive a pulley, d.

G represents the device for locking or securing the scaffold at any desired point upon the beams A A', and consists of a bar, e, having secured at its lower end a cross-bar, f. The bar e is slotted nearly its entire length, to receive a headed pin or bolt, e', projecting from the bar F, to allow of bar e being raised or lowered, the head of the bolt or pin e' preventing the disengagement of the bar e, and yet allowing it to slide freely upon the bar F. To the end of this bar e is secured a rope or chain, e'', which passes over the pulley d, and may be secured to any suitable fastening, d'.

H represents a rope or chain secured to the upper end of the scaffold, and passing over the pulley a'', by which means the scaffold is raised upon the beams A A'.

I represents a suitable platform arranged 70 upon the beam D.

The operation is as follows: The ends of the beams A A' are placed on the ground, the idler or roller bearing against the wall of the house. The scaffold is then raised to the desired height by means of the rope or chain H. The cross-bar f is then raised by means of the rope or chain e'', thus spreading the beams A A' apart, the inner ends of the bars A A' being cut away and the sockets or bearings of 80 the axis of the pulley a' enlarged, the ends of the axis being mounted on pivots, thus allowing a limited lateral movement of the bars A A', so that it is impossible for the scaffold to descend until the bar f is disengaged. The 85 wedging-bar f is held at any point between the bars A A' by fastening the rope e'', which is secured to said bar f, to the cleat d'. When it is desired to lower the scaffold, the same is slightly raised in order to loosen the bar e, 90 which is then allowed to drop, the scaffold then being gradually lowered by means of the rope H.

Having fully described my invention, what I claim as new, and desire to secure by Letters 95 Patent, is—

1. The combination, with two or more laterally-adjustable supporting-beams, connected at their upper ends and carrying a pulley, of a frame arranged upon said beams, and 100

having a rope or chain adapted to engage said pulley, and a bar having a transverse locking-bar secured at its lower end, and provided with a longitudinal slot adapted to receive a bolt or screw projecting from one of the bars of said frame, substantially as set forth.

2. The combination, with the laterally-adjustable beams A A', connected at their upper ends and carrying a pulley, of a frame or scaffold adapted to slide thereon, and having a rope adapted to engage said pulley, and consisting of the side beams, C C', braces b b' and c c', a beam, D, having an idler or roller,

d', bracing-beams E E', brace or bar F, having a pulley, d, and the locking device G, consisting of the slotted bar e and cross-bar f, and a rope or chain for operating said bars, substantially as set forth. 15

In testimony that I claim the foregoing as my own I have hereto affixed my signature 20 in presence of two witnesses.

JOHN THOMAS HASKELL.
